UNITED STATES PATENT OFFICE.

OTTO THIEME, OF ST. LOUIS, MISSOURI, ASSIGNOR TO MOON-HOPKINS BILLING MACHINE COMPANY, OF ST. LOUIS, MISSOURI, A CORPORATION OF MISSOURI.

CARRIAGE-RETURN MECHANISM.

1,294,726.

Specification of Letters Patent. Patented Feb. 18, 1919.

Original application filed May 20, 1916, Serial No. 98,853. Divided and this application filed March 27, 1918. Serial No. 224,961.

To all whom it may concern:

Be it known that I, OTTO THIEME, a citizen of the United States, residing at the city of St. Louis, State of Missouri, have invented a certain new and useful Improvement in Carriage-Return Mechanism, of which the following is a full, clear, and exact description, such as will enable others skilled in the art to which it appertains to make and use the same, reference being had to the accompanying drawings, forming part of this specification, in which—

Figure 1 is a side elevational view of the rear portion of a calculating machine provided with my improved carriage return mechanism.

Fig. 2 is a horizontal sectional view through the same.

Fig. 3 is a detail view of parts of the carriage return mechanism.

Fig. 4 is a side elevational view of the adjustable block and associate parts, said block being carried by the typewriter carriage.

Fig. 5 is a side elevational view of part of the carriage return mechanism.

Fig. 6 is a vertical sectional view of the parts shown in Fig. 5.

Fig. 7 is a cross sectional view on line 7—7 of Fig. 6.

Fig. 8 is a rear elevational view of the tally roll frame and its associate parts.

This invention relates to a new and useful improvement in carriage return mechanism for calculating machines, and is a division of an application filed by me May 20, 1916, Serial Number 98,853.

In the present case, there is disclosed a tally roll attachment for combined adding and billing machines of that class commercially known as Moon-Hopkins billing machines, in which there is a typewriting mechanism and an adding mechanism, the typewriting mechanism having the usual laterally movable paper carriage supporting a sheet of paper on which are printed words in connection with records on the printing type controlled by the adding mechanism. 119 and 268 indicate register wheels which are operated by the type-carrying racks 100, these racks at their rear ends operating printing segments 561 whose type make a printing impression on the tally strip. 500 indicates the casing or housing of the machine for inclosing the rear portion of the adding machine, to which casing are secured

the brackets 501 for supporting a grooved shaft 502 on which is a laterally movable frame 503 carrying a platen 504. Means are provided for vibrating this frame to make a printing impression from the segments 561 on the tally roll which is unwound from the source of supply 516.

In the parent case, I have disclosed means for tabulating the tally roll frame 503, and this present application is directed particularly to means for returning the tally roll frame to its home or starting position.

In United States Patent No. 1,120,862, granted December 15, 1914, upon an application for improvements in carriage return mechanism filed by me, I have shown a construction for returning the typewriter carriage from a constantly rotating motor shaft, this carriage return mechanism being rendered effective by the depression of what is known as a carriage return key. In the drawings, (see Figs. 5 and 6), 535' is a constantly running shaft driven from the motor drive of the machine, the upper end of which shaft is flattened, as shown in Fig. 6, for engagement with a clutch-carrying member 536 rotating in a plate 537. 538 is the companion clutch member carried on the lower end of the normally idle shaft 539, which shaft is mounted in a flexible bearing 540 seated in the stationary framing of the machine, (see Fig. 7). This flexible bearing 540 is held in position by a leaf spring 541, the bearing being inserted through suitable lateral openings in the framing of the machine so as to enable the upper end of the driven shaft to yield slightly, as will presently be described. The upper end of the driven shaft 539 (see Fig. 6) carries a gear wheel 542 which is designed to mesh with rack teeth 543 formed on the inner face of the escapement bar 521. The carriage return mechanism, including the gear wheel 542, is mounted in the frame of the machine, while the escapement bar, having the rack teeth which mesh therewith, is carried by the tally-roll frame which is slidably mounted on the shaft 502 supported by the casing of the machine. This casing is removable and when the parts are assembled, if the teeth on gear 542 do not mesh exactly with the rack teeth 543, then the shaft 540 may yield slightly until, by a relative movement between the teeth, they are brought into proper mesh with each other; likewise,

the escapement bar 521 and the lower end of frame 503 may yield outwardly slightly for the same purpose. Thus, in assembling the parts, if the teeth of the rack 521 do not 5 properly mesh with the teeth of gear 542 or are "cocked", either the gear or the rack will yield until, by a relative movement of the parts, the teeth are brought into proper mesh with each other. So, likewise, in vibrating the platen, the teeth of rack 521 are moved away from the gear 542 so as to be practically out of mesh therewith to prevent any lateral movement of the platen during the time that the platen is making a 10 printing impression, in the event that there should be an accidental movement of gear 542 at this time. However, when the platen frame is retracted, escapement rack 521 is again moved to engage the gear 542, 15 when the parts are in normal position, whereby the carriage return mechanism is enabled to operate the tally roll paper carriage only when the platen thereof stands retracted. 20

25 As shown in Fig. 6, it will be observed that the bracket in which the shaft 539 is mounted, has a knife edge bearing at its lower portion which permits a rocking movement of the shaft, the upper end of 30 said shaft finding bearing in the yielding block 540. The opening in the bracket above the knife edge bearing is made slightly larger than the shaft 539 to permit this movement. A set screw 540^a is employed 35 at the back of the yielding block 540 which set screw, in conjunction with the jam nut mounted thereon, enables the upper end of shaft 539 and the gear wheel 542 to be adjusted toward and from the teeth on the 40 escapement bar 521. The clutch bearing member 536 has an annular groove at its lower end in which are received the members of a plate 544, which plate is held upwardly by means of a spring 545. A post 45 546 mounted in a vertical bearing in the fixed frame bracket has its upper end located under a pin 547 carried by a rock arm 548 pivotally connected to the track plate 520 which is fixedly secured to the rear wall 50 of the casing 500.

The escapement bar 521 has a cam face 521^c at one end thereof which is designed to engage the pin 547 and depress the plate 544 and the clutch carrying member engaged thereby when the tally-roll carriage moves, or is moved, by the carriage return mechanism to its extreme right-hand position. This cam face 521^c, however, is so located with respect to the first notch and 55 shoulder (521^a and 521^b) of the escapement bar that the momentum of the carriage is relied upon to cause the cam face 521^c to depress the pin 547, to disengage the clutch members, whereupon the spring 526, connected to the tally-roll carriage asserts itself

and causes the tally-roll carriage to move leftwardly, to a slight extent, until the cam face 521^c has disengaged from the pin 547 and the shoulder 521^b is brought into engagement with the spring element 527^a of the escapement pawl for the tally-roll carriage, as fully set forth in the parent case. 70

When the plate 544 has thus been temporarily depressed by the rocking of the arm 548, as above described, (and the tally-roll carriage is at its starting position at the right,) the clutch members are held separated by means of a lever 549 (see Figs. 3 and 5) which lever is pivotally mounted on a frame portion of the machine and has 80 a shoulder on its lower end to engage over and hold the plate 544 depressed. The engaging position of the lever with respect to the plate 544 is effected by means of a spring 550. The upper end of lever 549 85 lies immediately to the rear of the sliding bar 551 having guiding slots formed therein, whereby the same may be supported by the framing of the machine and guided in its movement—screws being employed to 90 pass through the slots to hold and guide the bar 551 (see Fig. 3). The forward end of bar 551 carries a tappet 552, which tappet is provided with an inclined or cam face at its forward edge, said tappet 552 95 being so constructed that as the typewriter carriage with its bar 39 travels leftwardly, it will not operate the bar 551. It is only when the typewriter carriage travels toward the right that the bar 551 is operated. 100

The notched bar 39, which is carried by and movable with the paper carriage of the typewriting machine, is provided with an adjustable block 553 having a cam face projection 554 (see Figs. 3 and 4) which, 105 in the movement of the typewriter carriage, is designed at the proper moment to operate the bar 551, releasing the plate 544, and permit upward movement thereof to effect an engagement between the clutch members 110 of the carriage return mechanism. When the carriage reaches its extreme position at the right, the cam face 521^c will depress the pin 547 and with it, the plate 544, and disengage the clutch members. This position 115 of the tally-roll carriage is abnormal, and when the clutch members are disengaged, the spring 526 will move the carriage leftwardly a short distance until the escapement pawl is engaged by a shoulder 521^b 120 in which position of the tally-roll carriage, the cam face 521^c is disengaged from the pin 547. The return mechanism for the tally-roll carriage, is rendered effective by the position of the typewriter carriage and the adjustable block 553 thereon, the clutch members of said return mechanism being 125 disengaged by the cam face 521^c. This carriage return mechanism for the tally-roll carriage is separate and distinct from the 130

carriage return mechanism for the typewriter carriage, which latter may be of the construction shown in United States Patent No. 1,120,862, granted to me December 15, 5 1914, though it derives motion for its constantly driven shaft 535' from the same source of power, to wit, the motor drive for the calculating machine; the constantly driven shaft 535' (see Figs. 1 and 2) has a 10 miter gear 557' at its lower end which meshes with a companion gear 556 on shaft 557 whose forward end is driven by the gears 558 which are in turn driven from the motor.

15 What I claim is:

1. In an apparatus of the character described, the combination of a tally roll carriage, tabulating mechanism coöperating therewith, and a carriage return mechanism 20 which is automatically rendered effective to return said carriage to its home position after the final operation of said tabulating mechanism.

2. In an apparatus of the character described, the combination of a tally roll carriage, tabulating mechanism coöperating therewith, carriage return mechanism operable from a constantly rotating shaft, and means for entraining said shaft with said 30 carriage to return the latter after final tabulating operation is effected.

3. In an apparatus of the character described, the combination of a laterally movable paper carriage, a tally-roll carriage, 35 tabulating mechanism for said tally-roll carriage, carriage return mechanism for said tally-roll carriage, and means operated by said first mentioned paper carriage for rendering said tally-roll carriage return mechanism effective.

4. In an apparatus of the character described, the combination of a laterally movable paper carriage, a tally-roll carriage, tabulating mechanism for said tally-roll carriage, carriage return mechanism for 45 said tally-roll carriage, and plural means for rendering said carriage return mechanism effective and ineffective, one of said means being operable by the laterally movable paper carriage and the other by the tally-roll carriage.

5. In an apparatus of the character described, the combination of a laterally movable paper carriage, an adjustable stop carried thereby, a tally-roll carriage, tabulating mechanism for said tally-roll carriage,

carriage return mechanism for said tally-roll carriage, and plural means for rendering said carriage return mechanism effective and ineffective, one of said means being operated by the laterally movable paper carriage and the other by the tally-roll carriage, said first mentioned means being operated by the adjustable stop on the first mentioned carriage.

6. In an apparatus of the character described, the combination of a paper carriage, a yielding rack carried thereby, a pinion engaging said rack, a yielding bearing for said pinion, and means for rotating 70 said pinion at predetermined positions of the carriage.

7. In an apparatus of the character described, the combination of a tally-roll carriage, carriage return mechanism coöperating therewith, a separately operable paper carriage, means thereon for rendering said tally-roll carriage return mechanism effective, and means on the tally-roll carriage for rendering said return mechanism ineffective.

8. The combination of a yielding vibratable frame constituting a carriage for supporting paper, means for vibrating said frame, an escapement rack carried by said frame, and a carriage return gear for meshing with said rack in its normal or retracted position.

9. The combination of a yielding vibratable frame constituting a carriage for supporting paper, means for vibrating said frame, an escapement rack carried by said frame and movable therewith, a carriage return gear designed to engage said rack when said carriage frame is in its normal or retracted position, and means operable in any lateral position of the carriage for actuating said return gear whereby the carriage is restored to its starting position.

10. The combination of a vibratable tally-roll carriage and means for positioning the same laterally in one direction, a returning mechanism for moving said carriage in an opposite direction, another paper carriage having an arched bar, adjustable blocks mounted on said bar, and means whereby 105 said carriage returning mechanism for the tally-roll carriage is rendered operative as said adjustable blocks pass a predetermined point.

In testimony whereof I hereunto affix my 110 signature this 21st day of March, 1918.

OTTO THIEME.
